Primary Examiner—Paula A. Mortimer
Attorney, Agent, or Firm—Pennie & Edmonds LLP[57] **CLAIM**

The ornamental design for a zippered glove, as shown and described.

DESCRIPTION

FIG. 1 is a dorsal view of a first embodiment of a zippered glove showing our new design;
 FIG. 2 is a palmer view thereof;
 FIG. 3 is a left side elevational view thereof;
 FIG. 4 is a right side elevational view thereof;
 FIG. 5 is a top plan view thereof;
 FIG. 6 is a bottom plan view thereof;
 FIG. 7 is a dorsal view of a second embodiment of a zippered glove showing our new design, the difference being the contrasting elastic back and wave pattern;
 FIG. 8 is a palmer view thereof;
 FIG. 9 is a left side elevational view thereof;
 FIG. 10 is a right side elevational view thereof;
 FIG. 11 is a top plan view thereof; and
 FIG. 12 is a bottom plan view thereof.
